UNITED STATES PATENT OFFICE.

LEE C. SHARP, OF PLATTSMOUTH, NEBRASKA, ASSIGNOR TO AMERICAN CAN COMPANY, OF NEW YORK, N. Y., A CORPORATION OF NEW JERSEY.

CAN HEADING AND FLANGING MACHINE.

1,389,703.

Specification of Letters Patent. Patented Sept. 6, 1921.

Application filed April 22, 1916. Serial No. 92,941.

To all whom it may concern:

Be it known that I, LEE C. SHARP, a citizen of the United States, residing at Platts-
mouth, in the county of Cass and State of
Nebraska, have invented certain new and
useful Improvements in Can Heading and
Flanging Machines, of which the following
is a specification.

My invention relates to the making of
sheet-metal cans, and particularly to ma-
chines for flanging the ends of sheet-metal
can-bodies and for securing the heads on
such can-bodies. It is the object of my in-
vention to provide a combined flanging and
heading machine, simple in structure and
rapid in operation, wherein the ends of cy-
lindrical can-bodies may be flanged out-
wardly, as for double-seaming of heads
thereon, and wherein one or both heads may
be applied thereto and double-seamed, rolled
or folded thereon substantially with the same
operation as the flanging of the can-body.
A further object of my invention is to pro-
vide, in a die-flanging machine for can-
bodies, means whereby the can-cover or head
may form the working-face of the die and
the stop for limiting the length of the flange,
so that wear of the actual die is avoided
and the head partly secured to the body
simultaneously with the flanging operation,
and so that the edge of the head or cover
may be pre-rolled inward to a point sub-
stantially the same as that ordinarily reached
by the first rolling or folding of a double-
seaming operation. A further object of my
invention is to provide in a machine of this
kind a plurality of flanging dies and seam-
ing rollers so that by the distribution of
wear thereon frequent readjustment thereof
is rendered unnecessary. A further object
of my invention is to provide, in combina-
tion with such a machine, novel means for
rotating the chucks or dies which hold the
cans, and positive means for feeding or ad-
vancing the can-carrying devices, such that
the forward movement thereof may be either
continuous, or alternately retarded and ac-
celerated, or fully intermittent, at the will
of the operator, and without the use of pawl-
and-ratchet devices, brakes, or other mecha-
nism heretofore commonly used for obtain-
ing such movements. Further and more
specific objects of the invention will appear
hereinafter.

In the accompanying drawings, Figure 1 55
is a partial front elevation and partially a
longitudinal vertical section of a machine
embodying my invention, Fig. 2 is an end
elevation of the major part thereof, being a
section on the plane of the line 2—2 of Fig. 60
1, Fig. 3 is a transverse section on the plane
of the line 3—3 of Fig. 1, Fig. 4 is a detail
longitudinal section on the diagonal plane
of the line 4—4 of Fig. 2, Fig. 5 is a detail
transverse section on the plane of the line 65
5—5 of Fig. 1, Fig. 6 is a detail section on
the same plane as Fig. 2, showing a dif-
ferent position of certain parts, Fig. 7 is a
detail transverse section on the plane of the
line 7—7 of Fig. 1, Fig. 8 is a detail section 70
on the approximately horizontal plane of
the lines 8—8 of Figs. 1 and 2, Fig. 9 is a
detail section through a part of a can-body
and the head therefor, approaching the posi-
tion at which the end of the body is flanged 75
into the rolled edge of the head, and Figs.
10 and 11 are detail sectional views show-
ing the seam, at successive stages of forma-
tion.

In the illustrated embodiment of my in-
vention I provide a suitable horizontal bed 80
10 which is supported at a convenient height
by legs 11 arranged at the ends thereof. At
the ends of the bed, bearing-standards 12
are fixedly mounted thereon and in said 85
standards are journaled the end-portions of
a horizontal main-shaft 13. At the central
part of the main-shaft there is secured
thereon a carrier-wheel 14 having in the
peripheral portion thereof a plurality of 90
semi-cylindrical pockets of which the axes
extend parallel with the main-shaft and are
equidistantly spaced circumferentially of
the wheel. The main portions of said pock-
ets are adapted to receive and support cylin- 95
drical can-bodies 15, and near one side of the
wheel the pockets are annularly grooved or
bored out to a sufficiently larger diameter to
receive heads or covers 16 for the can-bodies
and to sustain them in alined axial relation 100
with the bodies 15 which rest in the pockets.
The bodies and heads are fed to the carrier-
wheel through a vertical chute 17 having
separate channels for series of said bodies
and heads disposed in superposed relation, 105
so that the same are moved by gravity into
the pockets of the wheel. The structure of
the carrier-wheel and feed-chute are common

in the art of can-making, particularly in can-heading machines, and will be understood without further explanation.

- At each side of the carrier-wheel there are rotatable and longitudinally-movable spindles which are held in axial alinement with the pockets of the carrier-wheel and carry at their inner ends, adjacent to the wheel, suitable chucks or dies for engaging the can-bodies and heads contained in the pockets of the wheel. The said spindles are carried by turret-wheels 18 and 19 which are secured on the main-shaft at the right and left sides of the carrier-wheel, respectively, as viewed in Fig. 1. The turret-wheels at the ends thereof adjacent to the carrier-wheel fit revolubly within bearing-rings 20 having foot-portions which rest upon and are secured to the bed 10. The upper portions of said bearing-rings serve for the support of the feed-chute 17, which is connected therewith by bars 21, as shown. The right turret-wheel 18 has a series of longitudinally movable and non-rotatable stems 22 which at their outer ends, or those remote from the carrier-wheel, are flattened at one side and have revolubly mounted thereon rollers 23 of which the axes are radial to the main-shaft 13. Said rollers 23 fit within a channel or groove formed between radially-extending flanges of a track-ring or stationary groove-cam 24 which is secured to the adjacent bearing-standard 12 concentrically with the main-shaft. By means of said track-ring and rollers the desired longitudinal movements are imparted to the stems 22 during rotation of the main-shaft. Rotation of the stems relatively to the turret-wheel is prevented by pins 25 which extend therefrom into slots in the outer sides of the wheel, as shown. The inner ends of the stems 22 are bored out to form bearings in which the spindles 26 are held revolubly, the inner ends of the pins 25 extending into annular grooves in the spindles to hold them in fixed longitudinal relation to the stems. The ends of the spindles at the closed ends of the bearings therefor, are pointed or cone-shaped and the end-thrust of the spindles during the operation of the machine is received on said points, so that the friction is reduced to a minimum.
- Flanging-dies 27 are secured on the inner ends of the spindles 22 adjacent to the carrier-wheel, and operate as hereinafter described, to flange the adjacent ends of the can-bodies.
- The left turret-wheel 19 has two series of longitudinally-spaced and alined bearings in which the spindles 28 are revoluble and axially movable. Said spindles carry at their inner ends the dies or chucks 29 and are alined axially with the spindles of the opposite turret-wheel, and with the pockets of the carrier-wheel. On the intermediate por-

tions of the spindles 28, between the bearings thereof, are secured small pulleys 30 whose axial length is less than the distance between the spindle-bearings, so that longitudinal movements of the spindles are permitted. A belt 31, driven from a suitable pulley arranged above the machine, passes around the series of pulleys 30, engaging those located for the time being at the sides and around the lower part of the turret-wheel, and thus serving to rotate at high speed the respective spindles on which the pulleys are carried. The relation of said belt and pulleys is clearly indicated in Figs. 1 and 5. At their outer ends the spindles 28 are shouldered to a smaller diameter than the body-portions thereof, and said reduced portions pass revolubly through saddles 32, being retained in fixed longitudinal relation thereto by collars 33 secured on the ends thereof. The saddles 32 have arcuate faces which fit slidably on the peripheral edges of the radial flanges of a track-ring or stationary groove-cam 34, which corresponds with the track-ring 24 at the opposite end of the machine, being secured to the adjacent bearing-standard 12. On the inner sides of the saddles are revolubly-mounted rollers 32' which extend between the flanges of the track-ring, the same thus serving to impart longitudinal movement to the spindles during the rotation of the turret-wheel about the axis of the main-shaft.

Rotation of the main-shaft 13 is effected, preferably, by means of a special driving mechanism therefor arranged at one end of the machine and constructed as follows: The shaft is extended beyond the bearing-standard 12 and has secured thereon adjacent to said standard a large gear 35. On the portion of the shaft extending beyond said gear there is mounted a link or arm 36 which is swingable about the axis of the shaft, and in the lower portion of which the drive-shaft 37 is journaled on an axis parallel with that of the main-shaft 13. At its inner end the drive-shaft 37 carries a pinion 38 which meshes with the gear 35, and at the outer end there is secured a pulley 39 which is connected by means of a belt 40 with a suitable driving pulley located above the machine. The speed ratio of the pinion 38 and gear 35 is such that for each revolution of the pinion the gear will be turned through an angle the same as the angle between the axes of adjacent sets of the rotating spindles and accompanying mechanism carried by the main-shaft. Thus, in the structure shown, there being eight sets of the spindles and pockets in the carrier-wheel, the pinion is so proportioned as to make eight revolutions to one of the gear. The bearing for the drive-shaft 37 is divided, and on the intermediate portion of the shaft between the two bearing-portions there is secured an 130

eccentric 41. The eccentric fits revolubly within a strap 42 having a slotted rod or stem 43 which passes slidably over a stud 44 extending out horizontally from a lug 45 at the end of the bed 10. At the lower end of the swinging link 36 there is an arm 46 having therein an arcuate slot concentric with the shaft 13, said slotted arm fitting slidably around the stud 44 adjoining the end of 10 the lug 45. On the stud 44, between the arm 46 and the eccentric-rod 43, there is a cylindrical collar 47 which may be either integral with the stud or fixedly secured thereon, and of which the diameter is 15 greater than the width of the slots in the arm 46 and rod 43. On the end of the stud there is secured a handle 48 by which the stud may be turned to screw the same in and out of the lug 45 and thus move the 20 collar 47 axially. In the adjacent sides of the arm 46 and rod 43, adjoining opposite ends of the slots therein, the said arm and rod have cylindrical counterbores therein, into which the collar 47 may be moved by 25 screwing the stud inwardly or outwardly with respect to the lug 45. When the stud is screwed inwardly, so that the collar 47 passes into the counterbored pocket 49 in the arm 46, the swinging arm 36 is held by 30 the stud in fixed relation to the machine frame, and the collar 47 is disengaged from the eccentric-rod. Thus, when the stud is in the described position, the drive-shaft revolves on a fixed axis, and the eccentric 35 works idly, the eccentric-rod merely reciprocating upon and rocking slightly about the axis of the stud, while the gear 35 is driven at a uniform speed by the pinion 38. By screwing the stud outwardly to such a 40 position as shown in Fig. 8, at which the collar 47 enters the counterbore of the eccentric-rod, the swinging link 36 is released so that it may oscillate about the axis of the main-shaft, and the end of the eccentric-rod 45 becomes pivotally connected with the stud so that the only movement permitted to said rod is that of oscillation about the axis of the stud. Then, during rotation of the drive-shaft 37, an oscillatory movement is 50 imparted by the eccentric 41 to the swinging-link 36, and the axis of the shaft 37, of the pulley 39 and pinion 38 reciprocates in an arcuate path concentric with the axis of the main-shaft 13, between two extreme positions such as those shown in Figs. 2 and 6. During such oscillatory or reciprocating movement, the pinion 38 continues to drive the gear 35 and the main-shaft, but the movement imparted thereto is not uniform 55 as when the axis of the drive-shaft remains stationary. During each half-revolution of the drive-shaft in which the swinging movement is in the opposite direction to that in which the gear 35 is being driven, the swinging movement permits the pinion 60 to roll planetarily upon the gear, and the rate at which the gear is driven is reduced proportionally to the rate of the swinging movement. During the alternate half-revolutions of the drive-shaft the swinging movement is added to the normal or average movement imparted to the gear, whose movement is thus accelerated by the same amount by which it was retarded during the intervening half-revolutions of the drive-shaft, 70 it being obvious that, as the pinion and gear remain constantly in mesh with each other, the total movement imparted to the main shaft during one revolution of the drive-shaft remains the same as when the 80 axis of the drive-shaft is stationary. By properly proportioning the eccentric, the throw of which determines the extent of the swinging movement imparted to the drive-shaft, the retardation of movement of the 85 gear 35 may be such that it will momentarily come to a full stop, and when so proportioned the several stopping positions of the gear and main-shaft may be such that the several spindles, chucks and pockets of the carrier- 90 wheel will occupy like positions at each pause in the rotary movement of the main-shaft. It may be noted that the oscillatory movements imparted to the drive-shaft and the pulley 39 are substantially at right angles 95 with the length of the drive-belt 40, so that the tension of said belt will not be altered sufficiently to interfere with the driving action thereof. 100

At the rearward side of the bed 10, near the longitudinal center thereof, there is secured a bracket having a plurality of cylindrical bosses 50 thereon, with axial openings through them which are radial to the axis of the main-shaft 13. A similar boss 105 51 may be provided between the depending front and rear flanges of the bed, as shown in Fig. 3, and in all of the radial openings of said bosses there are slidably disposed stems 52. Said stems carry at their inner ends, adjacent to the carrier-wheel, forked heads in which are revolubly mounted the seaming and forming rollers 53. The stems 52 are pressed yieldingly inward toward the carrier-wheel by means of springs 54 arranged in the bore of the bosses 50 and 51 beneath the ends of the stems, and the compression of said springs may be varied by means of the adjusting-screws 55 which are screwed into the lower ends of the bosses 110 50 and provided with locknuts 56, as shown, for retaining them in adjusted position. The inward movement of the stems is limited by means of pins 57 which extend transversely through the stems into slots in the 115 sides of the bosses, said pins 57 also serving to prevent rotation of the stems within the bosses. On the inner end portion of one of the bosses 50 there is pivoted a lever 58, the same being divided so as to pass around the 120 130

- sides of the boss, and its pivot or fulcrum being formed by pins 59, as shown in Figs. 3 and 4. At one end said lever 58 has an inwardly-curved or hook-shaped portion 60
- 5 on which a beveled-edged roller 61 is revolvably mounted on an axis which is radial to the main-shaft 13. The other end of the lever extends longitudinally of the machine to a point adjacent to the outer portion of
- 10 the turret-wheel 19, and at said end is provided with an adjusting-screw 62 which is adapted for engagement by a series of raised cam-lugs 63 which are carried on the peripheral portion of said wheel, as shown.
- 15 A spring 64, arranged beneath the lever 58 adjacent to the side of the boss 50 on which it is pivoted, normally presses the end of the lever inwardly toward said cam-lugs 63. The roller 61 is adapted to be brought into
- 20 operation after one or more of the externally acting rollers has bent the can end flange and contained can body flange into a more or less inclined position (Fig. 6), and at such time the partly formed double seam
- 25 is or may be subjected to compressing roller action both external and internal, as shown, after which the compressed seam is bent inward tightly against the can body in the usual manner.
- 30 Referring now to the general operation of the described mechanism, power is applied thereto by means of the belts 31 and 40, with resultant rotational movement of the various parts in the directions indicated
- 35 by arrows in the several figures of the drawing, and the can-bodies 15 and heads 16 are supplied to the feed-chute, descending through the same to the carrier-wheel. For most operations, the control-stud 44 for the
- 40 swinging drive mechanism is set to the position shown in Figs. 1 and 8, at which the movement imparted to the main-shaft is variable, or alternately retarded and accelerated, as hereinbefore explained in connection with the description of structure and
- 45 operation of said driving mechanism, and the same is so constructed and arranged that the points of slowest movement thereof, or the stopping positions thereof when the retardation is great enough to cause stoppage of the movement, are reached when the carrier-wheel pockets are alined with the end of the feed-chute. At this feeding or receiving position the rotary spindles carrying the
- 50 dies 27 and chucks 29 are held in retracted position by the track-rings 24 and 34, so that the can-bodies and the heads are free to drop into the pockets of the carrier-wheel. As the parts are advanced to the
- 55 succeeding positions, however, the spindles are pushed inwardly by the track-rings, so that the dies 27 engage the open ends of the can-bodies adjoining the same, and the chucks 29 engage the heads 16 and push the
- 60 same onto the adjoining ends of the bodies.
- The dies 27 are so formed that as they are pressed into the ends of the can-bodies the latter are swaged or bent outwardly to form radially extending flanges thereon, of which the width is limited by a stop-shoulder at 70 the outer part of the die. This operation of flanging a can-body and of limiting the length of the flange by a stop is now common in the can-making art and will be readily understood. At the opposite end of the 75 can, however, a similar operation is performed, but in this case the can-head 16, of which the edge is pre-formed as shown in Fig. 9, constitutes itself the flanging-die, so that as the flange is formed on the end of 80 the body 15 said flange passes outwardly within the rolled edge of the head, and the inwardly turned edge forms the stop for limiting the length of the flange. Thus, at the conclusion of the inward movement of 85 the spindles, the flange and the rolled edge of the head may be in substantially the form shown in Fig. 10. The can ends, when preliminarily shaped and used as described, constitute flanging devices which are fed 90 into the machine as loose flanging die plates and emerge as parts of the flanged and headed cans. At about the time that the flanging of the ends of the can-body by the inward movement of the spindles is completed, the pulley 30 on the respective spindle 28 is engaged by the belt 31 and causes a rapid rotary movement of said spindle which is transmitted through the chuck 29 to the can-head and body, and thence to the 100 die 27 and spindle 26. At a time after the rotation of the can has been well started, the same reaches a position at which the rollers 53 engage the same and begin the rolling or folding of the edges of the head 105 to double-seam the same onto the body. The detailed form of the seaming rollers and the operation thereof in forming the seam is well understood in the art and need not be described in detail. It may be noted, 110 however, that at what may be termed the second stage of the seaming operation the roller 61 is advantageously employed in folding or tucking in the edge of the head between the can-body and the flange thereof, 115 as shown in Fig. 11, the said roller 61 being moved longitudinally of the can-body into operative position at the proper time by the movement of the lever 58 caused by its engagement by the cam-lugs 63; as before described. The roller 61 is the only one of the seaming-rollers that need be positively moved toward or away from the can-body. The rollers 53, are so positioned that they will properly engage the can-head to roll 120 and form the seam thereof, and as said rollers are pressed yieldingly toward the cans by the springs 54, they may yield sufficiently to permit the cans to pass by them without causing an excessive pressure there- 130

on. At the same time the springs 54 are held under an initial compression great enough to prevent yielding thereof except under a pressure greater than the minimum required to properly form the seam. The resistance of the flange of the can head or end 16 will be such that as the edge of the body 15 is pressed against it by the action of the flanging dies the body will be flared and flanged outwardly, even though the flange of the head be thereby pressed a little away from the vertical plane of the head. The first flanging roll 53 is formed with a beveled face to engage the flange of the head, as seen in Fig. 11, whereby the said flange, with the inclosed flange of the body, will first be restored to transverse or vertical position and then will be bent over toward the body, as seen in said figure, and the succeeding seaming rolls 53 will press the interlocked flanges tightly down upon the body of the can. After passing the last of the seaming rollers the cans approach the upper end of an inclined discharge-chute 65, shown in Fig. 3, and are released by outward movement of the spindles, so as to fall into said chute, whence they are conveyed to any desired position.

It will be obvious to those skilled in the art that by the provision of suitable seaming rollers for both ends of the cans, heads may be secured upon both ends thereof simultaneously, in the same manner in which the heads are secured upon one end by the machine constructed as herein described and illustrated. It will also be obvious that, by the use of an unusual number of the seaming rollers, the seaming operation may be so subdivided that each of the rollers may perform its quota of the work while the cans are moved past the same by the carrier-wheel, even though the movement of the carrier-wheel be made uniform and continuous. The special swinging driving mechanism, however, provides a means by which the cans may be caused to pause or dwell momentarily at those positions in which the rollers will work most advantageously, and the seaming operation thus expedited and made more certain, while the average rate of movement of the main-shaft remains the same, and as rapid as if the movement were uniform. The special advantage of the peculiar driving mechanism lies in the fact that whether the rate of driving is uniform or variable, it is always positively controlled and exact, and that it will operate at high speed without noise or vibration and without the use of brakes to check the movement of the heavy rotating parts. The belt drive for the rotating chuck-spindles also has the advantage of smooth and noiseless operation, and of great simplicity as compared with gear-driven spindles.

Now, having described my invention, what I claim and desire to secure by Letters Patent is:

1. The combination of a can end chuck, a can body chuck, can ends formed with double flanges and adapted to form flanges on the edges of the can bodies, said double flanges having flange-limiting stops, means for placing said can ends and unflanged can bodies successively in alinement between said chucks, and means for decreasing the distance between said chucks until the edge of the can body is engaged with the flange of the can end, and for continuing to decrease said distance until the said edge of the can body is formed with a radially presented double seaming flange. 75

2. The combination of a can end chuck, a can body chuck, can ends formed with double flanges and adapted to form flanges on the edges of the can bodies, said double flanges having flange-limiting stops, means for placing said can ends and unflanged can bodies successively in alinement between said chucks, and rigid non-yielding means for decreasing the distance between said chucks until the edge of the can body is engaged with the flange of the can end, and for continuing to decrease said distance until the said edge of the can body is formed with a radially presented double-seaming flange. 95

3. The combination of a can end chuck, a can body chuck, can ends formed with double flanges and adapted to form flanges on the edges of the can bodies, said double flanges having flange-limiting stops, means for placing said can ends and unflanged can bodies successively in alinement between said chucks, means for decreasing the distance between said chucks until the edge of the can body is engaged with the flange of the can end, and for continuing to decrease said distance until the said edge of the can body is formed with a radially presented double seaming flange, and double-seaming mechanism arranged to form the flanges of the can end and can body into a tight double seam. 105

4. The combination of a can body chuck, an opposed chuck, means for placing can bodies successively in alinement between said chucks, means for producing a double-seaming flange on the edge of the can body the same consisting of a plate separably fitting over the said opposed chuck and having an outwardly extending flange which has a peripheral curved surface arranged to be engaged by the unflanged edge of the can body, said surface being rounded in directions away from the can body and also radially outward, said flange terminating in a sharp bend to act as a stop for the flange produced on the can body and terminate the outward extension thereof, and means 130

- for decreasing the distance between said chucks until the edge of the can body has been outwardly flanged and stopped as described.
5. The combination of a can body chuck, an opposed chuck, means for placing can bodies successively in alinement between said chucks, means for producing a double-seaming flange on the edge of the can body
- 10 the same consisting of a plate fitting over the said opposed chuck and separable therefrom with the can body and having an outwardly extending flange which has a peripheral curved surface arranged to be engaged
- 15 by the unflanged edge of the can body, said surface being rounded in directions away from the can body, and also radially outward, said flange terminating in a sharp bend to act as a stop for the flange produced
- 20 on the can body and terminate the outward extension thereof, and means for decreasing the distance between said chucks until the edge of the can body has been outwardly flanged and stopped as described.
- 25 6. The combination of double seaming mechanism, a can body chuck, an opposed chuck, means for placing can bodies successively in alinement between said chucks, means for producing a double-seaming
- 30 flange on the edge of the can body the same consisting of a plate separably fitting over the said opposed chuck and having an outwardly extending flange which has a peripheral curved surface arranged to be en-
- 35 gaged by the unflanged edge of the can body, said surface being rounded in directions away from the can body and also radially outward, said flange terminating in a sharp bend to act as a stop for the flange
- 40 produced on the can body and terminate the outward extension thereof, means for decreasing the distance between said chucks until the edge of the can body has been outwardly flanged and stopped as described,
- 45 and automatic means for feeding a succession of said plates between said chucks.
7. The combination of a can end chuck, means for holding a can body in axial alinement with said chuck, a can end held on
- 50 said chuck and shaped with a flange the inner surface of which is rounded away from the chuck and away from the position of the can body, the edge of said flange being bent sharply back and extended to-
- 55 ward said rounded surface to provide a stop for the edge of the can body flange as it is formed, whereby the latter is arrested from any but radial extension and is prevented from being bent back toward the can body,
- 60 and is caused to terminate in a radially presented edge, and means for decreasing the distance between said chucks until the can body edge is formed with a radially pre-
- 65 sented double-seaming flange interlocked with the can end flange.
8. The combination of a can end chuck, means for holding a can body in axial alinement with said chuck, a can end held on said chuck and shaped with a flange the inner surface of which is rounded away from the chuck and away from the position of the can body, the edge of said flange being bent sharply back and extended toward said rounded surface to provide a stop for the edge of the can body flange as it is formed, 70 whereby the latter is arrested from any but radial extension and is prevented from being bent back toward the can body, and is caused to terminate in a radially presented edge, means for decreasing the distance between said chucks until the can body edge is formed with a double-seaming flange, and double-seaming mechanism arranged to operate on said can end flange 75 after the can body flange has been formed 80 as described.
9. The combination of a can end chuck, means for holding a can body in axial alinement with said chuck, a can end held on said chuck and shaped with a flange the inner surface of which is rounded away from the chuck and away from the position of the can body, the edge of said flange being bent sharply back and extended toward said rounded surface to provide a 90 stop for the edge of the can body flange as it is formed, whereby the latter is arrested from any but radial extension and is prevented from being bent back toward the can body, and is caused to terminate in a radially presented edge, 95 rigid non-yielding means for decreasing the distance between said chucks until the can body edge is formed with a double-seaming flange, and double-seaming mechanism arranged to operate on said can end flange after the can body flange has been formed as described. 100
10. In a can heading and flanging machine, the combination of a heading chuck-die, an opposing can body flanging chuck-die, 110 means for moving said dies together for the purpose of clamping a can body and can head between them and for forming outstanding flanges on the ends of the can body, means for rotating said dies, means for 115 seaming down the flange of the can body while included within the flange of the can head, and means for conveying said dies relative to the seaming means with a variable movement, the least rate of movement 120 occurring when the cans are operated on by said seaming means.
11. In a machine of the class described, can-carrying means mounted to rotate on a fixed axis, seaming devices disposed near the 125 path of said can-carrying means, and actuating mechanism for said can-carrying means, said actuating mechanism including means having an alternately retarding and accelerating mechanical movement for con- 130

trolling the rate of movement of the driven parts, and means for throwing out of operation the retarding and accelerating means to cause a uniform movement of the driven

5 parts.

12. In a can heading and flanging machine, the combination of a heading chuck-die, an opposing can body flanging chuck-die, means for moving said dies together for 10 the purpose of clamping a can body and can head between them and for forming outstanding flanges on the ends of the can body, means for rotating said dies, a roll for tucking in the flange of the can head under the 15 can body flange and toward the end of the can, means for seaming down the flange of the can body while included within the flange of the can head, and means for conveying said dies relative to the seaming 20 means with a variable movement.

13. In a machine of the class described, a series of can-carrying devices mounted to rotate about a fixed axis and uniformly spaced circumferentially about said axis, means disposed near the path of said carrying devices for engaging the cans held thereby, and actuating means for said carrying devices including means having an alternately retarding and accelerating mechanical move- 30 ment for retarding the movement thereof at equal intervals, such that the carrying devices successively occupy like positions at the moments of greatest retardation.

14. In a machine of the class described, a 35 spindle-bearing wheel revoluble on a fixed axis, means for rotating the same on said axis, a series of spindles journaled in said wheel on axes parallel with the wheel-axis and spaced equidistantly about the same, 40 pulleys carried on said spindles, a drive-belt passing circumferentially about the series of pulleys to rotate the respective spindles as the successive pulleys are brought into engagement with said belt by the rotation of 45 the spindle-bearing wheel, means for clamping a series of cans in connection with said spindles to be rotated thereby, a can feed chute for delivering cans to the clamping means of spindles which are not in connection with said drive belt and a seaming roll 50 arranged to engage successive cans rotated by spindles which are in connection with said belt.

15. In a machine of the class described, a 55 revolvably mounted shaft, spindle-bearing wheels secured thereon in spaced longitudinal relation, a series of axially-aligned pairs of spindles revolvably mounted in said wheels on axes parallel with the shaft and arranged 60 equidistantly about said axis, actuating means for the shaft, means for moving the spindles of each pair longitudinally toward and away from each other during rotation of the shaft, pulleys carried by the set of spin- 65 dles on one of the spindle-bearing wheels, a

drive-belt passing circumferentially about the series of pulleys so as to engage at any moment all of the pulleys at one side of the wheel, and can-engaging dies carried on the adjacent ends of the spindles.

16. In a machine of the class described, a plurality of pairs of longitudinally aligned and rotatable spindles mounted on axes equidistantly spaced from and movable about a common axis, means for rotating said spindles, means for moving the spindles of each pair longitudinally toward and away from each other, can-engaging dies carried on the adjacent ends of the spindles, a plurality of seaming-rollers adapted for coöperation with 80 said dies and mounted on axes parallel with the spindle-axes and yieldable radially of the common axis about which the spindle-axes revolve, a roller coöperating with one of the seaming-rollers and mounted on an axis radial to said common axis and movable relative thereto, and an oscillatory lever carrying said coöperating roller.

17. The combination of a can end chuck, a can body chuck, can ends formed with 90 double flanges and adapted to form flanges on the edges of the can bodies in coöperation with said can end chuck and can body chuck, said double flanges of the can ends having flange-limiting stops, means for placing said 95 can ends and unflanged can bodies successively in alinement between said chucks, means for rotating said chucks, and means for decreasing the distance between said chucks until the edge of the can body is engaged with the flange of the can end and for continuing to decrease said distance until the said edge of the can body is formed with a flange.

18. The combination of a can carrier, can 105 rotating devices on said carrier, a plurality of seaming devices, means for actuating the carrier with a plurality of retardations and accelerations of speed as the cans are presented successively to and pass from the 110 several seaming devices, and adjustable means for causing said carrier to move with an even speed.

19. The combination of a can carrier, can 115 rotating devices on said carrier, a plurality of seaming devices, means for actuating the carrier with a plurality of retardations and accelerations of speed as the cans are presented successively to and pass from the several seaming devices, and adjustable means 120 for varying said retardations and accelerations of speed.

20. The combination of a can carrier, can 125 rotating devices on said carrier, a plurality of seaming devices, and means for actuating the carrier with a plurality of retardations and accelerations of speed as the cans are presented successively to and pass from the several seaming devices.

21. The combination with a relatively fixed 130

seaming device, of a can carrier, can rotating devices on said carrier, and means for actuating the carrier with gradual retardation and acceleration of speed as the cans are successively presented to and pass from said seaming device.

22. The combination with means for operating on cans, of a can carrier, can rotating devices on said carrier, and means continuously geared with the carrier for actuating the carrier with a plurality of gradual retardations and accelerations of speed as the cans are presented successively to and pass from said operating means.

15 23. In a mechanism for feeding cans for closing or other purposes, the combination of a movable can carrier, a toothed rack fixed thereon, a rotatable power pinion engaging said rack, and means for reciprocating said pinion in the direction of the movement of said rack and in the opposite direction.

25 24. In a mechanism for feeding cans for closing or other purposes, the combination of a movable can carrier, a toothed rack fixed thereon, a rotatable power pinion engaging said rack, means for reciprocating said pinion in the direction of the movement of said rack and in the opposite direction and adjustable connections for releasing the pinion from said reciprocating means and restraining the bodily movement of the pinion.

35 25. In a mechanism for feeding and closing cans, the combination of a movable can carrier, a toothed rack fixed thereon, a rotatable power pinion engaging said rack, means for reciprocating said pinion in the direction of the movement of said rack and 40 in the opposite direction, means for holding and individually rotating cans while on said

carrier, and seaming means to which the cans are presented by said carrier.

26. The method of double seaming can ends with can bodies, which consists in forming the can end with an outwardly and radially extending flange and with an abrupt return bend in said flange to act as a stop for the edge of the can body to determine the length of the flange to be formed on the can body, and then forcing the edge of the can body longitudinally against the flange of said can end and causing said edge to be flanged outwardly until the edge encounters said return bend, and thereby forming a lateral seaming flange on the can body which extends between outer and inner parts of the can end flange.

27. The method of double seaming can ends with can bodies, which consists in forming the can end with an outwardly and radially extending flange and with an abrupt return bend in said flange to act as a stop for the edge of the can body to determine the length of the flange to be formed on the can body, and then forcing the edge of the can body longitudinally against the flange of said can end and causing said edge to be flanged outwardly until the edge encounters said return bend, and thereby forming a lateral seaming flange on the can body which extends between outer and inner parts of the can end flange, and then rolling down and flattening the double seam so formed.
